UNITED STATES PATENT OFFICE.

WALTER F. PEET, OF PHILADELPHIA, PENNSYLVANIA.

DESIGN FOR AN EYE FOR GARMENT-HOOKS.

SPECIFICATION forming part of Design No. 24,272, dated May 7, 1895.

Application filed April 4, 1895. Serial No. 544,485. Term of patent 14 years.

To all whom it may concern:

Be it known that I, WALTER F. PEET, a citizen of the United States, residing in the city and county of Philadelphia, State of Pennsylvania, have invented and produced a new and original Design for Eyes for Garment and other Hooks, of which the following is a specification, reference being had to the accompanying drawings, forming part thereof.

10 The leading features of my design for an eye for a garment or other hook, are first, triangular or approximately triangular shaped feet, and next, the termini of said feet in opposite directions.

15 Figure 1 represents a perspective view of an eye embodying my invention. Fig. 2 rep-

resents a side elevation thereof. Fig. 3 represents a top or plan view thereof.

In the drawings, A designates an eye consisting of the top cross bar B, the legs C depending therefrom, and the feet D extending laterally and outwardly from the bases of said legs. The legs C are of triangular form, and their termini are on opposite sides of the legs as at E, F.

20 25 What I claim is—

The design for an eye for a garment, &c. substantially as described and shown.

WALTER F. PEET.
